UNITED STATES PATENT OFFICE.

CHARLES H. KENNEY, OF NEW LONDON, CONNECTICUT, ASSIGNOR, BY DIRECT AND MESNE ASSIGNMENTS, TO THE NON RECOIL GUN CORPORATION, OF NEW YORK, N. Y., A CORPORATION OF NEW YORK.

FIREARM.

1,174,165.

Specification of Letters Patent.

Patented Mar. 7, 1916.

Application filed June 12, 1915. Serial No. 33,643.

To all whom it may concern:

Be it known that I, CHARLES H. KENNEY, a citizen of the United States, residing in New London, in the county of New London and State of Connecticut, have invented 5 certain new and useful Improvements in Firearms, of which the following is a specification.

My present invention relates to an improvement in firearms, and more specifically to a device for neutralizing the recoil forces generated in all guns at the instant of discharge.

One of the main objects of the present invention is to provide a construction whereby the energy in the gases discharged from the gun muzzle is utilized to impress upon the gun a force opposite in direction to the recoil force acting on the gun whereby the 20 recoil force is substantially neutralized and obviated.

A particular object of the present construction is the use of a plurality of curved deflecting surfaces whereby the gases when 25 being discharged will continually and gradually change their direction, or rather of which deflecting surfaces, the entire surface extent will exercise a reacting force on the gases being discharged.

30 A particular feature of the invention is the provision of a plurality of curved discharging passages each being of a much smaller width than the diameter of the bore of the gun so that the discharging gases 35 will be so divided as to play on the greatest possible extent of surface area.

Still another feature of the invention is to so construct the curved passages that at no place can the discharging gases discharge 40 to the outside atmosphere in a straight path of movement, but must at some place or other be obstructed by a part of the deflecting surfaces, and in which the convex surfaces of the passages will tend to create a 45 vacuum so that work can be obtained from substantially every particle of discharging gases.

Still another object of the invention is the division of a plurality of passages for 50 discharging gases whereby the discharging gases will be divided into a plurality of jets without intervening spaces at the entrance to such passages, and the outlets of which

passages are so close to one another, that the discharging jets of gases will substantially unite with one another to form an integral volume without intervening friction-creating bodies of air between the several jets of discharging gases.

And a still further object of the present 60 invention is the provision of an arrangement whereby the discharging gases will be divided into a series of jets continually and gradually deflected and discharged in an integral volume without intervening 65 friction-creating bodies of air between the several jets of discharging gases and in a direction opposite to their original path of movement.

Another advantage in my construction is 70 the provision, in conjunction with my device, of an expansion chamber which is arranged at a suitable point between the gun barrel proper and my reactor so that the velocity of the expanding gases at the 75 muzzle of the gun is increased, thereby carrying a greater amount of energy into my reactor, to be there translated into counter-balancing opposition to the gun recoil.

These and other features, capabilities and advantages of the invention will appear from the subjoined detailed description of one specific embodiment thereof.

In the accompanying drawings, Figure 1 85 is a sectional view of my device, showing the details of construction; Fig. 2 is a sectional view of my device taken on line 1—1, Fig. 1, looking in the direction of the arrow; Fig. 3 is a fragmentary portion of the outer 90 case or reactor container; Fig. 4 is an end view of the same; Fig. 5 is a sectional view taken on line 5—5, looking in the direction of the arrow; Fig. 6 is a sectional view taken on line 6—6, Fig. 3, looking in the 95 direction of the arrow; Fig. 7 is a sectional view of the muzzle end of my device; Fig. 8 is a sectional view of the expansion chamber of my device; Fig. 9 is a perspective 100 view of a pair of my reactors in nested relative operative position; Fig. 10 is a side elevation of one of my reactors enlarged; Fig. 11 is an axial sectional view thereof; Fig. 12 is a front elevation of my device mounted for use; Fig. 13 is a side elevation, mounted for use; and Fig. 14 is a 105

diagrammatic view, showing the action of the gases upon one of the reactors.

By referring to Figs. 1, 7 and 8, it will be noted that as is there shown in the sectional view, my reactors in cross-section are substantially concavo-convex with the high points of the crescents pointing rearwardly toward the muzzle of the gun so that upon the outward rush of the gases upon the moment of discharge, and aided by the natural tendency of gases to immediately expand at the point of emission, the gases find their means of escape directed through a plurality of backwardly curved ports A, which 15 are arranged between the component reactor members forming the unit device. In order to more fully understand this, reference may be had to Figs. 9, 10 and 11, wherein it will be noted that the reactor members X 20 consist of a substantially annular concavo-convex portion B, generally noted by the fully shaded section, and that the outer surface C is so arranged as to nest or contact with the inner curved faces of the separators or ribs E, which separators in their 25 annularly spaced positions around the inner surface of the convex-concave member B form a plurality of isolated seats, which contact or nest with the fitted coinciding surface C and between which the channels or ports F are formed, thereby forming the 30 smooth curved gas passages A, and which passages are backwardly turned so that the oncoming gases in the bore of the gun are 35 intercepted by the adjacent lower ends of the crescents, expand outwardly through the curved passages A, and are redirected outwardly and backwardly toward the breech of the gun, thereby translating a 40 large portion of their velocity into forward-acting energy which counteracts the rearward "kick" or recoil due to the projectile momentum.

It is obvious that a greater or lesser number 45 of these reactor-disks may be arranged within the effective gas-expanding zone, and that each added reactor-disk in said effective zone will increase the reaction effort.

Further means is also provided on my device for rendering more available the energy 50 at the instant of discharge in order to obtain a greater efficiency from the given quantity of the expanding gases, and this provision is disclosed in Fig. 1, at G, and 55 comprises specifically a gas-expanding chamber H and an outwardly divergent chamber I, both of which contiguous chambers are preferably arranged, (as regards the flow of gases), intermediate of the 60 straight portion of the gun bore J, and the entrance into the reactor proper.

By means of the foregoing noted combined expanding chamber and divergent chamber, the outrushing gases are caused to 65 expand rapidly, thereby increasing the ve-

locity thereof through the greater increase in volume, as it is known that as a gas passes through a divergent nozzle, its volume is increased in a greater proportion than the cross-section of the channel and that for this reason its velocity and momentum are increased. The greater the expansion in the chambers H, I, the greater the velocity at this point. Obviously, this increase in the velocity and momentum of the discharging 75 gases creates a greater counter-effect upon my reactor, thereby adding materially to its reaction on the gun, and reducing the number of reactor disks necessary when this feature is omitted.

By referring to Fig. 14, wherein is shown a large section of one of my reactors, the arrows K represent the flow of gases in the direction of travel in the bore, the arrows L represent the direction of the gases as 85 they impinge upon the reaction portion F of the disks, the lines M—M denoting the imaginary annular line running through the middle of the portion F between its inner and outer edges. It is evident then that 90 the gases, as indicated by the arrows, K, L, L, while impacting against the surface F, are reversed as regards direction, and the point of reversal may be assumed to be at about the lines M—M above noted. Immediately thereafter the gases are directed backwardly by the portion F in the general direction of the arrows N, substantially in a direction toward the breech of the gun.

As the gas discharges along the bore of 100 the reactor, it is evident that this bore, generally denoted by O, forms substantially a continuation of the gun bore J, and that the bore O presents a plurality of divergent expanding chambers, due to the formation 105 of the reactor disks. Each one of the said chambers in its progressive sequence permits of successive expansions of the gas and redirects its energy of increased velocity so that while the bore O may be of substantially the same diameter throughout its 110 length, there is sufficient change of the bore contour to permit of the above-noted successions of expansion, and therefore successive changes in velocity as the flowing 115 gases expand to atmospheric pressure.

By referring to Fig. 2, which is a section of my device taken on line 1—1, Fig. 1, it will also be noted that the ports A themselves are substantially divergent, as 120 indicated at A¹, and owing to this conformation, the ribs or contoured seat members E are triangular in shape, being sharpened at their apexes near the bore, their bases being turned outwardly and being approximately the same width as the tension members P, which form the outer ribs or stress forming members of the casing, these ribs being tangentially surfaced at their sides, thereby forming a substantially di- 130

vergent opening P^1 , so that from the instant the discharging gases reach the first expanding chamber H , with its adjacent divergent nozzle I , the gas is also passed through transverse divergent openings and that a minimum amount of transverse non-reacting surface is presented to the outflowing gases.

The casing, which is generally denoted by Q , as indicated in Figs. 1, 3, 5, 6, 7 and 8, is provided with a solid gun engaging portion R , in which member there is a chambered cylindrical pilot part S , which may be smoothly machined, such as by grinding, in order that the true cylindrically surfaced end of the gun at T may be fitted with precision, and the inner portion of the said chamber S has cut thereon a plurality of suitable threads U , which threads engage with corresponding threads cut upon the muzzle of the gun V . This method of fitting is particularly adapted for insuring perfect alinement of the reactor device.

Extending from said solid portion R are arranged a plurality of tension members P , in the present instance eight, the tension members being preferably rectangular in cross-section, and arranged at the outer end of the said tension members there is formed an annular member W , which member has a suitable thread W^1 cut therein. While in the present instance I have shown the gun engaging portion R , the annular end W and the tension members P as being made of one piece, and such construction is within the scope of regular shop practice, it is obvious that the gun engaging portion R and the threaded ring member W might be separate members, and the tension members might be made in the form of bolts, means being provided on the members R and W to permit the proper engagement therewith of said bolts. In order to form a proper seat for the first reactor member of the group, the member R , near the place of connection with the rectangular members P and at the junction therewith of the divergent opening I , is provided with a rounded nose, such as Y , and against which is located the surfaces of the separators E . Thereafter, the predetermined number of reactor disks, having been placed in the casing Q , a compressing nut Z , having suitable threads thereon, is entered into the ring W of the said casing, and by a suitable wrench is screwed up to contact with the reactors, putting them under the desired pressure and locking all of them in place. A proper seat

Z^1 may be provided in the nut Z so that the same will contact accurately and form a perfect seat between the last reactor and the said nut. Owing to the method of nesting the reactor disks X , it will be seen that when sufficient tension has been exerted

upon the said disks by the nut Z , that the device is to all intents a single unitary structure.

While as previously noted, the gases at the moment of discharge tend to expand rapidly after ignition, it is obvious that the reactor will tend to restrict the gases in the expanding zone, and that therefore a certain amount of gases will be confined to a forward direction, namely those gases acting in the bore O of the reactor. It is therefore evident that upon the discharge of the gun, the projectile O^1 , (Fig. 7) during the outrush of the gases through the reactor, will act, through its inertia, in the nature of a valve, uncovering the succeeding ports A on its passage through the reactor, and that therefore the projectile receives added impetus from the thrust of the gases in the bore O until the energy thereof is spent by their exhaustion and discharge. In order to make this valve action effective, it is necessary that there be not too great a difference in dimensions of the diameter O^2 of the bore and the diameter O^3 of the projectile, so that this valve action of the projectile for gradually dispersing the gases through the ports A may be made very positive.

In the above-noted assembling, one of the precautions necessary to insure a proper assembling of the device is to have all of the ribs E lined up in such a manner that they will come immediately under the tension members P so that the continuation of the ports A in the said reactor members X will pass between said members P without obstruction, thereby forming complete passages A , as indicated in Figs. 1 and 2.

It is obvious that a number of modifications might be made in the structure of my device without altering, in any way, the principles involved, and while I have shown in the drawings and described my preferred form of construction, modifications may be made therein as a concession to manufacturing, without in any way departing from the spirit or scope of my invention.

I claim:

1. In a gun, a recoil reaction device comprising a chambered bore having a plurality of backwardly curved reaction passages substantially uniform in width and uninterrupted throughout their entire extent, the passages having convex surfaces, and the middle portion of said convex surfaces being disposed between the ends of such passages to obstruct the discharge therethrough in a straight line.

2. In a gun, a recoil reaction device comprising a chambered bore having a plurality of backwardly curved reaction passages uninterrupted throughout their entire extent, the passages having concave and convex wall members, the ends of each concave wall

member extending over the convex wall member.

3. A recoil reactor for guns comprising a plurality of like contoured reaction disks, 5 said disks being substantially concavo-convex, the surfaces thereof forming alternate nesting seats for each other and the space between two coacting surfaces forming apertures for the outlet of expanding gases, the 10 apertures also being formed by the convex and concave surfaces of the disks and the middle of the convex surface of an aperture being disposed between the middle of the concave surface of its aperture and a 15 line in which the ends of such concave surface are disposed.

4. As an article of manufacture, an annular gas reactor disk having its convex surface of greater curvature than its concave surface thereby producing a tapering conformation.

5. As an article of manufacture, an annular gas reactor disk having its convex surface of greater curvature than its concave 25 surface thereby producing a tapering conformation and having one of its surfaces interrupted by a plurality of like contoured ribs.

6. As an article of manufacture, an annular disk having a convex side and a concave side, and ribs arranged on one of said sides, said ribs being triangular, the base of said triangle being located at the perimeter of said disk, the apex of said triangle 35 being located at the inner portion of said disk so that only deflecting surfaces and no obstructing surface will be presented to the interior of the disk.

7. The combination in a gun, of a recoil 40 reaction device comprising a chambered bore having a plurality of backwardly curved reaction outlets therein an initial concave gas expanding chamber located between said gun and said reaction device, and a divergent 45 gas-expanding chamber disposed adjacent to said concave gas-expanding chamber and located between said concave expanding chamber and said reaction device.

8. A casing for holding a plurality of 50 recoil reaction plates in operative alinement with a gun bore, said casing having gun at-

taching means thereon and compressive recoil-disk adjusting means thereon, and ribs extending between said gun attaching means and said recoil-disk attaching means, the 55 ribs being sufficiently spaced apart to permit a discharge from between said plates to the outside atmosphere, said gun attaching means comprising a straight cylindrical gun-muzzle guiding-bore and threads in a 60 portion of said bore, said reaction disk-holding means comprising a threaded cap having a recoil-reaction disk-engaging seat thereon.

9. The combination in a gun, of a recoil 65 reaction device, a concave expanding gas chamber and a divergent nozzle intermediately located between the gun bore and said reaction device.

10. In a gun, a recoil reaction device comprising a chambered bore and a plurality of 70 backwardly curved reaction passages uninterrupted throughout their entire extent, the passages having concave and convex wall members, the middle of the convex wall 75 member being disposed between the middle of the concave wall member and a line that passes through the ends of such concave wall member.

11. In a gun, a recoil reaction device comprising a series of concavo-convex plates held together, there being gas reaction outlets formed between such plates, the convex surfaces of the plates having a greater 85 curvature than the concave surfaces to form substantially uniform passages with one another.

12. In a gun, a recoil reaction device comprising a series of concavo-convex plates held together, there being gas reaction outlets formed between such plates, the convex surfaces of the plates having a greater 90 curvature than the concave surfaces to form substantially uniform passages with one another and the middle of a convex surface 95 being disposed between the middle of a concave surface and a line that passes through the ends of such concave surface.
